SPRAYER OR ATOMIZER

Filed Feb. 9, 1928

Inventor:
Theodor Kübler
by Kirschbaum
Atty.

UNITED STATES PATENT OFFICE.

THEODOR KÜBLER, OF STUTTGART, GERMANY.

SPRAYER OR ATOMIZER.

Application filed February 9, 1928, Serial No. 253,164, and in Germany February 15, 1927.

My invention relates to sprayers or atomizers for liquids. It is an object of my invention to provide a device of this kind which can be directly connected with the tins or other receptacles in which the liquid, such as varnish, paint, lacquer or the like, is sold.

To this end I provide an open or closed frame, which may also have the form of a closed container and is adapted to take up the 10 tin or other liquid-receptacle, the contents of which shall be atomized. With the frame or container is connected a pump, compressor or the like, which may be permanently mounted thereon. I insert the tin or other receptacle in the frame or container and I introduce into the receptacle, when it is in position in the frame or container, the delivery pipe of the pump or compressor, so that the liquid in the tin or other receptacle is raised and 20 expelled by the pump, compressor or the like for atomization.

In the drawing affixed to this specification and forming part thereof an apparatus embodying my invention is illustrated diagrammatically.

In the drawing

Fig. 1 is a perspective illustration of the complete apparatus,

Fig. 2 is a perspective illustration of a tin 30 for the liquid to be sprayed,

Fig. 3 is a partly sectional elevation of the apparatus.

Referring to the drawing, *a* is a pump or compressor of some suitable type, *b* is a frame or container, on the cover plate *h* of which the pump is permanently or detachably secured, and *e* is the delivery pipe of the pump, which projects downwardly into the frame or container *b*. The frame or container is closed at its bottom end by a hinged lid *c* and a clip *i* is provided for holding the lid in closed position. *d* is a spring secured to the lid on the inside, *g* is a tin containing the liquid to be sprayed or atomized, *h* is a short pipe projecting from the top of the tin, and *f* is a cushion to which the upper edge of the pipe *h* is held by the thrust of the spring *d*.

In operation the lid *c* is opened, the tin *g*, the stopper or other closure of which has been 50 removed from the pipe *h*, is inserted in the

container *b* from below and the lid *c* is closed by the clip *i*. This is the position of parts illustrated in Fig. 1, in which a tight connection is made by the cushion *f* and the delivery pipe *e* of the pump or compressor *a* projecting into the tin *g*, so that the liquid is discharged from the tin by the compressor, and is sprayed or atomized.

My invention is particularly designed for applying varnish or other preserving coatings to lacquered surfaces, for instance motor-car bodies, but it may also be used for other purposes, for instance for spraying wax solution onto parquet floors, and generally wherever it is desired to atomize an expensive, dangerous, or readily volatilized liquid.

It is to be understood that I am not limited to a frame or container in which the bottom is hinged and the top plate is fixed, as obviously these parts might be arranged conversely. 70 The pump or compressor might also be permanently or detachably secured to the hinged lid instead of being secured to the fixed cover plate, and other means than a hinge might be provided for connecting the lid and the container.

I wish it to be understood that I do not desire to be limited to the exact details of construction shown and described for obvious modifications will occur to a person skilled in 80 the art.

I claim:—

A sprayer or atomizer comprising a frame adapted to receive a liquid-receptacle and having a fixed top plate, a pump or compressor secured to said top plate, a delivery pipe connected with said compressor and extending axially into said container, a hinged lid at the bottom of said container, means for holding said lid in closed position, resilient means 85 on said lid for exerting axial thrust on said receptacle, and a cushion secured below said fixed top plate and adapted to be engaged by said receptacle under the action of such thrust.

In testimony whereof I affix my signature.

THEODOR KÜBLER.
